AUGER BUCKET FOR MACHINES FOR DIGGING CAISSENS AND THE LIKE

Ewald H. Siebel, Chicago, Ill.; Emeline R. Siebel, executrix of said Ewald H. Siebel, deceased, assignor, by mesne assignments, to Spencer, White & Prentis, Incorporated, New York, N. Y., a corporation of Connecticut

Application September 6, 1932, Serial No. 631,850

12 Claims. (Cl. 255—19)

This invention relates to apparatus for digging deep holes of large diameter such as caisson holes and the like. It has more particular reference to improvement in the earth conveying digging 5 augers provided for use in such apparatus.

A principal object of the present invention is the provision of an improved earth conveying and digging auger for use in the apparatus of the character of that shown in the application 10 of Hilmar Emil Satre, Serial Number 517,845, filed February 24, 1931 for improvements in Caisson boring machines, which application has matured into Patent No. 1,998,591, issued April 23, 1935 and been assigned to Spencer, White and Prentis, 15 Incorporated, New York, N. Y., a corporation of Connecticut.

An important object of the invention is the provision of an excavating and conveying auger bucket for use in the machine of said application 20 and other machines which will be self discharging when the bucket has been lifted out of the hole for emptying and through the action of devices wholly or substantially wholly automatic in their action.

The invention contemplates in this regard the performance of the digging operation by arranging the bucket in contact with the floor of the hole and its rotation to cause cutting elements on the bottom of the bucket to dig the earth and 25 deliver it through slots in the bucket bottom, until the bucket has received a full charge of excavated earth. The bucket is then raised to above the ground and to a discharge station, whereupon rotation is accomplished in the opposite direction 30 to quickly discharge the excavated earth back out through the slots, preferably through the influence of devices which press the earth down into the bucket as it is emptied and which produce a relative rotation between the slotted bucket 35 bottom and the contained charge of earth, so that the charge is sliced back through the slots at relatively high speed. Additionally the invention contemplates the automatic timing of the 40 operation of the last mentioned devices to start them into operative action immediately after the arrival of the bucket in upper or discharge position, to render them ineffective at completion of the discharge operation, and to return them to initial position as an incident to the start of 45 downward movement of the bucket for the next succeeding excavating step.

Another important object of the invention is improvement in side cutter construction for auger buckets of the character described, and more particularly to provide a side cutter construction

adapted to cooperate with the discharge mechanism earlier mentioned.

An important object of the invention is the provision of a side cutter for a rotating digging and conveying auger adapted for the forming of caisson holes and the like, which shall be of sturdy construction and which may be moved into and out of digging positions by the rotative movements of the auger itself and without the necessity of providing special control mechanisms.

The invention contemplates the attainment of the several foregoing objects and purposes in apparatus sufficiently sturdy in construction and efficient in operation to permit of the digging of deep holes for caisson construction and other 15 purposes, of large diameter as for example, four, six, and eight feet and more.

Numerous other objects and advantages of the invention will be apparent from the following description which taken in connection with the 20 accompanying drawings discloses a preferred embodiment thereof.

Referring to the drawings,

Figure 1 is a side elevation of a combined digging and conveying auger bucket embodying the 25 instant invention, parts of the excavating apparatus being disclosed;

Figure 2 is a vertical section through the structure of Figure 1, taken substantially on the line 2—2;

Figure 3 is a top plan view taken substantially 30 on the line 3—3 of Figure 2;

Figure 4 is a bottom plan view of the auger bucket shown in Figure 1;

Figure 5 is a detail section taken substantially 35 on the line 5—5 of Figure 1.

The caisson apparatus of the co-pending Satre application above mentioned employs a main digging shaft which extends down through the hole with its axis in registration with the axis of the 40 hole, and a combined digging and conveying bucket is mounted on this shaft and slides from digging to discharge positions. The bucket is keyed to the shaft against independent rotation so that rotation of the shaft imparts digging rotation to the bucket. So much of this apparatus as is thought necessary to an understanding of the instant invention is shown on the drawings.

Reference character 11 indicates a front I-beam member of the main frame of the machine, 50 and reference characters 12 front to back structural frame members. A digging shaft 13 extends from the bottom of the hole up into the frame of the machine and into gear connection (not shown) to a source of power adapted to 55

impart desired rotation. The shaft 13 is provided at opposite sides with outwardly extending keys 14 arranged throughout its length.

The combined digging and conveying bucket of 5 the instant embodiment of the invention comprises a unitary rigid cylindrical auger body 15 and bottom plates 16 secured in fixed engagement with the bottom edge of the cylindrical part 15 throughout substantially 90 degrees as indicated at 17. The bottom edge of the part 15 is 10 cut back from the opposite ends of a diameter indicated at *a-a* in Figure 2 in the form of a helix throughout 180 degrees and each bottom member 16 is extended beyond its connection 17 15 with the cylindrical body 15 to provide a slot 18 between its edge 19 and the adjacent (but lower) edge 21 of the adjacent or other member 16.

A digging element 23 is secured by bolts 24 or the like to extend forwardly across the slot 18 20 from the forward edge of each bottom member 16, and each of these digging elements is or may be provided with serrations or teeth 25. Digging elements 26 are also provided for attachment to the body 15 at 27 and extend forwardly as indicated at 28 to provide lower side and reaming cutters arranged at the floor of the hole.

The auger bucket thus constructed is mounted upon a sleeve 31 embracing the shaft 13 and having keyways 32 matching the keys 14 of the shaft. 30 Plates 33 are provided at the bottom to connect the inner edges of the bottom members 16 with the sleeve 31.

Openings indicated at 36 are arranged through opposite sides of the body 15 to receive earth excavated by reamers, the construction and mounting of which will now be described. Reamer blades 37 are mounted upon the free edges of doors 38 pivoted on inclined pivots 39 for movement from a position closing the openings 36 outwardly into digging positions where the digging or reaming elements 37 cut away the side wall of the hole and the doors 38 sweep the earth into the interior of the bucket. The doors 38 are so mounted that when the bucket rotates in its cutting action, the reamers or digging elements 37 40 are swung outwardly into engagement with the sides or wall of the hole. Engagement with the presented surface causes the reamers or digging elements 37 to cut into the earth until stopped by limiting chains 41 secured to the doors at 42 and to the body 15 at 43. Continued rotation of the bucket causes reaming of the hole and delivery of the excavated earth through the openings 36. The diameter of cut may be varied by increasing 50 or decreasing the chain lengths 41. When, however, the bucket is given sufficient rotation in the reverse direction, the center of gravity of the doors 38 having been lifted in the opening movement of the doors, the doors automatically close 55 by gravity as soon as the reaming or excavating elements 37 are freed of their engagement with the wall of the hole.

As has been earlier explained, means are provided for automatically accomplishing discharge of each charge of earth received into the bucket as soon as the bucket is lifted to a discharge position above the surface. The bucket is lifted from the hole, sliding upwardly on the shaft 13 65 by means of two cables 44 secured at their lower ends at 45 in a cross-yoke 46 rotatably connected to the upper end of sleeve 31, relative rotation between this sleeve and the yoke 46 permitting rotation of the bucket with the shaft 13 without 70 entangling or twisting of the cables 44. The yoke 75

46 is or may be pivotally mounted at 50 to provide for uneven lengths of the cables 44.

An inner sleeve or shell 51 of unitary rigid structure is mounted within the body 15 and extends substantially throughout its height. Its bottom edge 52 is arranged within slots 53 provided between the higher portions of the bottom members 16 and the side of the body 15 of the bucket. A spider 54 connected at its ends at 55, 5 is arranged within the top of the sleeve 51 to 10 loosely embrace the sleeve 31 and is supported by a ball bearing 56 from the sleeve 31. The shell 51 is normally locked to the body 15 by two locking dogs 57 pivoted at 58 in oppositely extending arms of the spider 54, the outer ends of these 15 dogs being arranged in registering slots 59 and 61 of the sleeves 15 forming the cylindrical part 20 of the bucket body and 51 arranged within the bucket. The sleeve 51 is provided with openings 60 which register with openings 36 in the bucket 25 body.

Two downwardly extending posts 62 are secured to brackets 63 carried by the frame members 12. The lower ends of these posts are arranged in vertical registration with tails 64 of the dogs 57. 25 Figure 3 shows the position of the bucket and its several parts as the bucket approaches the upper end of its travel. Further upward movement of the bucket from the position shown causes the posts 62 to engage the dogs and swing them from 30 the horizontal position shown up out of the slots 59 and 61 and into rigid clips 65 where they are engaged to prevent rotation of the shell 51 while the bucket is in its uppermost or discharging position. 35

Thus arranged the bucket may be rotated by rotation of the shaft 13 in direction opposite to that given the bucket in digging to cause the upper edges 19 of the bottom member 16 to cut away the charge of earth to deliver it out through 40 the slot to empty the bucket.

Means are or may be provided to continually press down the charge as the shell is emptied. A plunger 71 is arranged within the shell 51 upon a bushing 72 embracing the sleeve 31. A threaded engagement is provided between the sleeve 31 and the bushing 72, this threaded engagement consisting in the present instance of a thread 73 on the sleeve 31 and a spiral recess 74 in the bushing. Two keys or ribs 75 are arranged upon 50 the inner surface of the sleeve 51 in position for engagement with slots 76 in the plunger. These keys extend from adjacent the bottom to adjacent but below the upper position of the plunger. A roll 70 of diameter equal to or less than the 55 width of these keys is mounted above each in position to engage the under side of the plunger.

At the commencement of rotation of the shaft 13 to discharge the shell, the plunger 71 is arranged above the tops of the keys 75 and moves down and angularly until it rides upon the rollers 70. Thereafter continued rotation of the shaft 13 causes the plunger slots 76 to register with and pass over the rollers 70 and to descend along the keys 75 under the influence of the thread 65 73 to press the charge out of the slots at the bottom of the bucket. When the plunger reaches the bottom it is disposed beneath the lower ends of the keys 75 and may rotate idly with the shaft.

A dog 77 is pivoted at 78 at the lower end of 70 each key which may be swung up out of the way as the plunger starts this idle rotation and which operates as a latch to reengage a slot 76 when the sleeve 51 is rotated in the opposite direction. The dogs 77 then form continuations of the keys 75

and cause the thread to lift the plunger back to its upper normal position.

As the bucket is lowered after discharge, the dogs 51 reengage in the slots 59 and 61 to accomplish conjoint rotation of the sleeve 51 and bucket 15 during the digging.

To facilitate rotation between the body 15 of the bucket about the sleeve 51 while the discharge is being accomplished rollers 19 arranged in carriers 81 secured in the body 15 may be provided to engage the opposed outer surface of the sleeve 51.

It is thought that the invention and many of its attendant advantages will be understood from the foregoing without further description, and it will be apparent that various changes may be made in the construction and arrangement of the parts without departing from the spirit and scope of the invention or sacrificing many of its material advantages, the form hereinbefore described being merely a preferred embodiment thereof.

I claim:

1. An auger for digging caisson holes and the like, comprising a cylindrical bucket having radial earth receiving slots in its bottom and provided with digging elements for digging on the floor of the hole and delivering the excavated earth through said slots into said bucket, and means within the bucket for discharging the excavated earth received through said slots out through the slots in a tangential direction after the bucket has been removed from the hole for discharge.

2. An auger for digging caisson holes and the like, comprising a cylindrical bucket having earth receiving slots in its bottom and provided with digging elements for digging on the floor of the hole and delivering the excavated earth through said slots into said bucket, and means within the bucket for rotating the charge of excavated earth carried by the bucket to accomplish discharge of said earth through said slots.

3. An auger for digging caisson holes and the like, comprising a cylindrical bucket having radial earth receiving slots in its bottom and provided with digging elements for digging on the floor of the hole and delivering the excavated earth through said slots into said bucket, and means within the bucket when at a discharge position for comminuting and moving the earth contained in the bucket out through said slots to empty the bucket.

4. An auger for digging caisson holes and the like, comprising a cylindrical bucket having earth receiving slots in its bottom and provided with digging elements for digging on the floor of the hole and delivering the excavated earth through said slots into said bucket, and means within the bucket when at a discharge position for removing the earth contained in the bucket out through said slots to empty the bucket, said means including a device for rotating the charge of earth relatively to the slots in the bottom of the bucket.

5. An auger for digging caisson holes and the like, comprising a cylindrical bucket having earth receiving slots in its bottom and provided with digging elements for digging on the floor of the hole and delivering the excavated earth through said slots into said bucket, and means within the bucket when at a discharge position for moving the earth contained in the bucket out through said slots to empty the bucket, said means including a device pressing upon the contained earth for forcing it out through the slots as the bucket is emptied, and a device for comminuting the

earth to facilitate the discharge through the slots.

6. An auger for digging caisson holes and the like, comprising a cylindrical bucket having earth receiving slots in its bottom and provided with digging elements for digging on the floor of the hole and delivering the excavated earth through said slots into said bucket, and means within the bucket when at a discharge position for moving the earth contained in the bucket out through said slots to empty the bucket, said means including devices conjointly operable, one, for producing relative rotation between the charge of earth in the bucket and, two, for pressing downwardly on the material as the bucket is emptied.

7. An auger for digging caisson holes and the like, comprising a cylindrical bucket having digging elements on its bottom and discharging devices in its interior, said digging devices being operable to dig and fill the bucket upon rotation of the bucket in one direction, and said discharging devices being operable by relative rotation in the opposite direction.

8. An auger for digging caisson holes and the like, comprising a cylindrical bucket having earth receiving slots in its bottom, and provided with digging elements for digging on the floor of the hole and discharging the excavated earth through said slots into said bucket, said bucket having also an earth receiving opening in its side, and a door for said opening provided at its free edge with a reaming element for enlarging the diameter of the hole, said door being pivoted to swing from an opening closing position to a digging position by rotation of the bucket in its digging operation, in combination with an inner cylindrical earth receiving shell rotatable relative to the auger bucket, and means associated therewith to forcibly expel the charge of earth.

9. In an excavating apparatus, a cylindrical auger having on its lower face earth receiving slots and provided with digging devices adjacent the slots discharging thereinto, means to rotate the auger in one direction to cause the digging devices to feed the earth through the slots to the interior and in the opposite direction to discharge the earth outwardly through said slots, a cylindrical earth retaining shell concentrically disposed within the auger and having openings registering with the auger slots, means to lock the shell and auger together for common rotation in a digging direction, means to release the connection between the shell and auger prior to rotation of the auger in a discharging direction, and means associated with the inner shell for release to expel the earth from the inner shell and to hold the shell against rotation with the auger in a discharging direction, the expelling means comprising a follower resting upon the earth in the shell and means to feed the follower downwardly upon reverse rotation of the auger.

10. In an excavating apparatus, a cylindrical auger having on its lower face earth receiving slots and provided with digging devices adjacent the slots discharging thereinto, means to rotate the auger in one direction to cause the digging devices to feed the earth through the slots to the interior and in the opposite direction to discharge the earth outwardly through said slots, said means comprising a rotatable guide shaft disposed axially of the auger and having a splined engagement therewith, a cylindrical earth retaining shell concentrically disposed within the auger and having openings registering with the auger slots, means to lock the shell and auger together for common

rotation in a digging direction, means to release the connection between the shell and auger prior to rotation of the auger in a discharging direction, and means associated with the inner shell for release to expel the earth from the inner shell and to hold the shell against rotation with the auger in a discharging direction, the expelling means comprising a follower resting upon the earth in the shell and means to feed the follower downwardly upon reverse rotation of the auger.

11. In an excavating apparatus, a cylindrical auger having on its lower and side faces earth receiving slots and provided with lower and side digging devices adjacent the slots discharging thereinto, means to rotate the auger in one direction to cause the digging devices to feed the earth through the slots to the interior and in the opposite direction to discharge the earth outwardly through said slots, said means comprising a rotatable guide shaft disposed axially of the auger and having a splined engagement therewith, a cylindrical earth retaining shell concentrically disposed within the auger and having openings registering with the auger slots, means to lock the shell and auger together for common rotation in a digging direction, means to release the connection between the shell and auger prior to rotation of the auger in a discharging direction, and means associated with the inner shell for release to expel the earth from the inner shell

and to hold the shell against rotation with the auger in a discharging direction, the expelling means comprising a follower resting upon the earth in the shell and means to feed the follower downwardly upon reverse rotation of the auger.

12. In an excavating apparatus, a cylindrical auger having on its lower face earth receiving slots and provided with digging devices adjacent the slots discharging thereinto, means to rotate the auger in one direction to cause the digging devices to feed the earth through the slots to the interior and in the opposite direction, to discharge the earth outwardly through said slots, a cylindrical earth retaining shell concentrically disposed within the auger and having openings registering with the auger slots, means to lock the shell and auger together for common rotation in a digging direction, means to release the connection between the shell and auger prior to rotation of the auger in a discharging direction, and means associated with the inner shell for release to expel the earth from the inner shell and to hold the shell against rotation with the auger in a discharging direction, the expelling means comprising a follower resting upon the earth in the shell and means to feed the follower downwardly upon reverse rotation of the auger, said means comprising a helix rotatable with the auger and having a threaded connection with the follower.

EWALD H. SIEBEL. 30
